UNITED STATES PATENT OFFICE

WILLIAM H. KEUNE, OF CARLINVILLE, ILLINOIS

WASHEBOARD SHIELD

Application filed December 13, 1928. Serial No. 325,859.

The present invention relates to improved attachments for washboards and has for its principal object to provide a shield to prevent the splashing of the water upon the garments of the user during the washing operation.

Another object is to provide an attachment of this character which may be easily and quickly secured to and detached from the board and which may be used upon various boards so that the shield may be removed from an old board after the same becomes worn and placed in position upon a new board.

Other objects and advantages reside in the special construction, combination and arrangement of the various elements forming the invention, as more fully hereinafter described and claimed, reference being had to the accompanying drawing forming part hereof, wherein like numerals refer to like parts throughout the specification and in which

Figure 1 is a front elevational view of the attachment shown in position upon the washboard,

Figure 2 is a vertical sectional view therethrough taken along a line 2—2 of Figure 1, and

Figure 3 is a transverse sectional view taken along a line 3—3 of Figure 1.

Referring now to the drawing in detail, the invention comprises a shield indicated generally at 5 and preferably constructed of substantially heavy gauge sheet metal and adapted to rest upon the top 6 of the washboard 7. The rear edge of the shield is formed into a flange 8 and is bent downwardly and under the rear edge of the top 6 and the forward edge of the shield protrudes forwardly of the front edge of the top 6 and is curved downwardly as shown at 9.

The forward edge 9 is also curved toward its side edges. At the under side of the forward end 9 of the shield is arranged a strip

of metal 10 disposed in parallel relation with the front edge of the top 5 and secured along its outermost edge to the shield by soldering, welding or the like. The rear edge of the strip 9 is spaced slightly away from the under side of the shield and is adapted to receive one edge of an attaching plate 11, the opposite edge of said plate being disposed under the forward edge of the top 6. Aligned openings are formed in the plate 11 and the shield 5 for receiving bolts 12 for wing nuts 13 threaded thereon for detachably securing the plate in clamping position at the under side of the shield, as clearly illustrated in Figures 2 and 3 of the drawing.

It will be apparent from the foregoing that the shield may be easily and quickly secured in position upon the board and when in position, as illustrated, will adequately prevent the splashing of water upon the garments of the user.

It is obvious that the invention is susceptible of various changes and modifications without departing from the spirit thereof, or the scope of the appended claims, and I accordingly claim as my own all such forms of the invention to which I am entitled.

I claim:

1. A shield of the class described comprising a sheet of rigid material having a washboard engaging flange formed along one edge for engaging the rear edge of the top of the washboard and a clamping plate detachably secured to the under side of the shield for engaging the forward edge of the washboard top.

2. A shield of the class described comprising a sheet of rigid material having a washboard engaging flange formed at one edge and adapted for engaging the under side of the rear edge of the top of the washboard, said shield having its forward edge extended outwardly from the front of the washboard and curved downwardly, a member secured to the shield adjacent the front edge

90

thereof and with its rear edge free and disposed in spaced relation from the shield, a clamping plate having one edge arranged between the member and the shield and with its other edge disposed in position for engagement with the under side of the top of the washboard and means for securing said top of the washboard between said plate and the shield.

10 In testimony whereof I affix my signature.
WILLIAM H. KEUNE.
